(57)

CLAIM

The ornamental design for a shoe sole, as shown and described.

DESCRIPTION

FIG. 1 is a lateral side view of a shoe sole;

FIG. 2 is a top view thereof;

FIG. 3 is a medial side view thereof;

FIG. 4 is a front view thereof;

FIG. 5 is a rear view thereof;

FIG. 6 is a front perspective view from the lateral side thereof; and,

FIG. 7 is a rear perspective view from the lateral side thereof.

The short, broken lines shown in the drawings of the shoe sole illustrate portions of an article of footwear or stitching that form no part of the claimed design.

1 Claim, 7 Drawing Sheets
